FREQUENCY MODULATION DETECTION

Harry E. Thomas, Haddonfield, N. J., assignor to
Radio Corporation of America, a corporation of
Delaware

Application June 6, 1942, Serial No. 446,027

11 Claims. (Cl. 250—27)

My invention relates to detection of angular velocity-modulated carrier waves, and more particularly to oscillator networks adapted for detection of frequency modulated (FM) carrier waves.

One of the main objects of my invention is to provide a demodulator of FM waves, wherein the demodulator comprises an oscillator network having a tank circuit resonant to the mean, or center, frequency of applied FM wave energy, while input circuits are provided which are tuned to frequencies on either side of center frequency and differing from the latter by equal frequency values.

Another object of the invention is to provide an oscillator system having but a single oscillator tube; the tube having a pair of resonant input circuits to which FM energy is applied, and the input circuits being oppositely mistuned relative to the oscillator tank circuit frequency which is the mean, or center, frequency.

Other objects of my invention are to improve the operation of the aforesaid types of demodulators; a noise limiting circuit, quickly responsive to noise pulses, acting to render the oscillator ineffective for the duration of the pulse.

Still other objects of my invention are to improve FM demodulators by providing an oscillator type of FM demodulator; the demodulator being capable of inherent limiting, and also being adapted to supply considerable gain for audio amplification.

The novel features which I believe to be characteristic of my invention are set forth with particularity in the appended claims; the invention itself, however, as to both its organization and method of operation will best be understood by reference to the following description taken in connection with the drawings in which I have indicated diagrammatically several circuit organizations whereby my invention may be carried into effect.

In the drawings:

Fig. 1 schematically shows a demodulator according to the invention.

Fig. 2 shows the discriminator characteristic of the demodulator.

Fig. 3 shows a modification of the invention.

Fig. 4 shows the oscillator characteristic of Fig. 3.

Referring now to the accompanying drawings, wherein like reference characters in the different figures designate similar circuit elements, in Fig. 1 the tuned circuit 1 is the resonant output circuit of an intermediate frequency (I. F.) ampli-

fier, for example. In FM reception the superheterodyne receiver is universally employed. Those skilled in the art are fully acquainted with the networks commonly employed prior to the limiter stage. Assuming, by way of specific illustration, that the receiver is to be operated in the assigned FM band of 42 to 50 megacycles (mc.), those skilled in the art know that the resonant selector circuits will have to be sufficiently broad to pass the maximum frequency deviations of the carrier, or center, frequency F_c of each channel.

In FM broadcasting at present, the channel width is 200 kilocycles (kc.), although at the FM transmitter the carrier is deviated to a permissible maximum of 75 kc. on each side of F_c . Of course, this invention is not limited to the 42-50 mc. band, nor is it restricted to a deviation range of 75 kc. on each side of center frequency. Furthermore, the generic term "angular velocity-modulated carrier wave" is used in this application to denote that either frequency or phase modulated carrier waves may be received.

Assuming, now, that the converted FM waves of a selected channel have been amplified by one or more I. F. amplifiers, the amplified I. F. voltage across output circuit 1 is applied to the input electrodes of limiter tube 2. The latter acts to minimize amplitude modulation effects in the FM wave energy. The effects may be caused by external noise impulses, tube noise, round-top resonance curves of the cascaded selector circuits, man-made static etc. The limiter stage is well known. Its input circuit 3 is tuned to F_c , as is circuit 1. F_c is the operating I. F. value, and the latter can be chosen from a range of 2 to 20 mc., as for example 4.3 mc.

The circuits 1 and 3 will have a pass band of at least 150 kc., and preferably wider, so as to pass efficiently all the frequency deviations. The limiter has a grid circuit network 4—5 whose time constant is short. The constants of the limiter tube are so chosen that the "input-output" characteristic rises linearly up to a desired input amplitude; thereafter it flattens out. Hence, any carrier amplitude increases, representative of undesired amplitude variation, are automatically minimized. During operation there will be a voltage developed across grid resistor 4 in response to grid current flow through the latter. If a sharp noise pulse is applied to the receiver, a direct current voltage is quickly developed across resistor 4 due to the aforesaid grid current flow. This voltage is used to control the detection of FM wave energy, as will be later explained.

The limited FM energy output of tube 2 is applied to a novel type of demodulator circuit. The latter essentially comprises a pair of oscillator tubes 6 and 7. The control grid 8 of tube 6 is coupled to the limiter plate by coupling condenser 9. The control grid 10 of oscillator 7 is coupled to the limiter plate by coupling condenser 11. Each cathode of the oscillator tubes is at ground potential. The grid of each oscillator tube is connected to ground by a respective grid leak resistor.

A direct current source has its positive terminal B+ (the source being omitted from the drawings) connected to the plate of the limiter tube. The resonant circuit designated F₁ has the high potential side thereof connected to the plate side of the coupling condenser 9; the low potential side of circuit F₁ is connected to the B+ terminal. Similarly, the resonant circuit designated F₂ has its high potential side connected in parallel to the limiter plate. The B+ terminal is connected to the low potential side of circuit F₂.

Oscillator tube 6 has its plate 12 connected through a blocking condenser 12' to the coil of a resonant tank circuit designated F_c. The resonant circuit F₁ is reactively coupled to the tank circuit of oscillator tube 6. The plate 13 of oscillator tube 7 is connected by blocking condenser 13' to the coil of its tank circuit also designated F_c. Here, again, the circuit F₂ is reactively coupled to the tank circuit of oscillator tube 7. The symbols F_c applied to the plate resonant circuits of oscillator tubes 6 and 7 signify that they are each tuned to the center, or carrier, frequency of the FM waves. The tank circuits F_c are returned to ground through the B+ terminal.

The symbol F₁ applied to the resonant grid circuit of tube 6 indicates that said circuit is tuned to a frequency on one side of F_c. The symbol F₂ applied to the resonant grid circuit of tube 7 signifies that the said grid circuit is tuned to a frequency on the opposite side of F_c. In Fig. 2 there are shown the respective "frequency-oscillator output" characteristics A and B of each oscillator. It will be seen that oscillator tube 6 has its peak value of output at F₁; oscillator 7 has its peak output value at F₂. The cross-over point of the two characteristics A and B is located at F_c. It is desirable to locate F₁ and F₂ at equal frequency distances from F_c; further, it is preferred to have F₁ and F₂ beyond the maximum frequency swing of the carrier. The limits of frequency swing are indicated by the vertical dotted lines on either side of F_c.

The FM signal energy is applied to the grid circuits of oscillator tube 6 and 7; regenerative feedback is provided in each case by coupling between each resonant plate circuit and its grid circuit. Normally, and in the absence of FM waves, both oscillators oscillate at F_c. As the applied FM wave energy deviates in frequency from F_c, the oscillatory output of each oscillator tube will vary as indicated in Fig. 2. Each oscillator is readily able to follow the applied FM wave swings if the instantaneous frequency values fall between F_c and the frequency of the particular grid circuit. Hence, the plate circuits of the oscillators have currents of variable amplitude flowing therein; furthermore, these currents correspond to the modulation signal variations applied to the carrier at the FM transmitter.

To derive the modulation signal energy from the variable-amplitude oscillatory energy, the plates 12 and 13 are connected to opposite ends

of primary winding 14 of transformer 15. In other words, the plate circuits of the oscillators are in push-pull as regards the audio components thereof. If the modulation signals are in the audio range, each plate is connected to its end of the transformer winding through a respective radio frequency choke 16. The midpoint of coil 14 is connected to the positive terminal of a direct current source. Only the audio signal variations pass to the following audio network. Each of the oscillators functions inherently to perform a certain degree of limiting. Accordingly, the limiting due to tube 2 is augmented.

In addition, the voltage developed across resistor 4 is applied over lead 18-18' and 18-18'' to the control grids 8 and 10 of the respective oscillator tubes. Thus, should a sudden pulse of noise be applied to the receiving system, then the voltage across resistor 4 will be applied quickly to the oscillator grids. The noise control voltage could be sufficiently negative to bias each oscillator tube to cut-off. As soon as the noise pulse disappears, the bias voltage quickly leaks off the oscillator grids and the demodulator is again normally operative. Where the noise pulses occur rapidly, the effect is to produce rapid "gaps" in demodulation. If the "gaps" are not too rapid they will not seriously affect the audio output wave form. Network 4-5 should have as rapid a time constant as possible. It should allow the noise control voltage to act as quickly as possible in blocking the oscillator, and so reduce any residual noise that passes the limiter. Discharge of condenser 5 should be rapid so that return of the oscillator grid voltage to normal is rapid.

In Fig. 3 I have shown a simplification of the system. Here, a single oscillator tube 20 replaces the two oscillator tubes 6 and 7 of the system of Fig. 1. The plate 21 is connected to the high potential side of tank circuit F_c; that is, a single tank circuit replaces the two tank circuits of Fig. 1. The resonant grid circuits F₁ and F₂ are now arranged in series in the plate circuit of an I. F. amplifier 22. The oscillator grid 23 is connected by the blocking condenser 24 to the high potential side of circuit F₁. The grid leak resistor 25 is connected from the oscillator grid to ground. The B+ terminal of the direct current energizing source is connected to feed the I. F. amplifier and oscillator tube plates through the respective coils of the resonant circuits. Each of circuits F₁ and F₂ are reactively coupled to the tank circuit F_c. The normal oscillation frequency in the absence of FM waves is at F_c, and is of low amplitude.

The amplifier 22 may be a limiter. On the other hand, a special diode rectifier 40 may be used to provide the quick-acting noise control voltage. The diode is coupled, as at 3-3', to the amplifier input. The lead 52 feeds the noise control voltage to the control grid 23 of the oscillator. Since the oscillator may be operated at high levels, considerable conversion gain of I. F. to audio may be realized with very small inputs to the prior amplifier, or limiter. As stated before, there is secured augmented limiting action due to the inherent limiting action of the oscillator. It is, also, pointed out that the sensitivity of discrimination is increased by this arrangement.

The latter function follows from the fact that the circuit F_c acts as the primary circuit of a transformer whose secondary circuit 40' is tuned to the same frequency F_c as the primary circuit. The circuit 40' may be the resonant input circuit

of a discriminator-rectifier network of well-known type. For example, the discriminator-rectifier shown by S. W. Seeley in U. S. Patent 2,121,103, granted June 21, 1938, may be employed. This network comprises the diode rectifiers 50 and 51 in opposition. The diode anodes are connected to opposite sides of the input circuit 40'. The midpoint of coil 41 is connected by blocking condenser 42 to the plate side of resonant primary circuit F_c' .

The series-arranged load resistors 60 and 61, connected between the diode cathodes, have the junction thereof connected to the midpoint of coil 41 through choke coil 70. The lower end of resistor 61 is grounded, while the audio voltage is taken off from the upper end of resistor 60. Reactive coupling, shown by the dotted bracket, exists between the primary circuit F_c' and secondary circuit 40'.

The curve C in Fig. 4 shows the "frequency-oscillator output" characteristic of the oscillator network in the system of Fig. 3. From the curve it will be seen that the strength of oscillation increases with departure in either direction from F_c . The system $F_1-F_2-F_c'$ and tube 20 form an oscillator which is locked in synchronism with incoming FM waves from amplifier 22. A coupling between F_c' and 40' produces quadrature phase voltage in circuit 40'. The midpoint of coil 41 is connected through condenser 42 to the high potential side of circuit F_c' so that these circuits together with opposed diodes 50-51 and associated elements constitute a conventional discriminator.

However, the slope of the discriminator characteristic is increased, according to my invention, by having the oscillator voltage increase as the frequency departs from F_c , instead of decreasing as does the voltage on the primary of the usual discriminator of the aforesaid Seeley type. Hence, the usual S-shaped curve of the discriminator is made more steep due to the action of the oscillator on primary circuit F_c' .

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In combination with a source of angular velocity-modulated carrier waves, a demodulator which comprises an oscillatory network, said network comprising a pair of resonant circuits, one of said resonant circuits being tuned to a frequency located a predetermined frequency amount on one side of the mean frequency of said waves, the second circuit being tuned to a frequency located on the opposite side of said mean frequency at an equal frequency spacing value, means for applying said wave energy to both of said resonant circuits, an electron discharge system having an output circuit across which is developed modulation voltage, means for regeneratively feeding back to said two resonant circuits oscillatory energy of said mean frequency and a quick-acting gain control circuit connected to said applying means and responsive to sudden noise impulses, said control circuit having a connection to said electron discharge system for preventing operation of the latter for the duration of the impulses.

2. In a frequency modulated carrier wave

receiver, a network providing frequency modulated carrier wave energy, a demodulator comprising a pair of electron discharge tubes, each tube having an input electrode and an output electrode, separate resonant networks coupling said source to respective input electrodes of said tubes, said resonant networks being oppositely mistuned by equal frequency amounts relative to the center frequency of the frequency modulated wave energy, a resonant tank circuit reactively coupling each of the aforesaid resonant circuits and a respective output electrode of each tube, said resonant tank circuits each being tuned to the aforesaid center frequency, and a common push-pull output circuit connecting said output electrodes.

3. In a frequency modulated carrier wave receiver, a network providing frequency modulated carrier wave energy, a demodulator comprising a pair of electron discharge tubes, each tube having an input electrode and an output electrode, separate resonant networks coupling said source to respective input electrodes of said tubes, said resonant networks being oppositely mistuned by equal frequency amounts relative to the center frequency of the frequency modulated wave energy, a resonant tank circuit reactively coupling each of the aforesaid resonant circuits and a respective output electrode of each tube, said resonant tank circuits each being tuned to the aforesaid center frequency, a common push-pull output circuit connecting said output electrodes, and additional means, responsive to undesired noise impulses having an amplitude level above a predetermined value, for rendering said tubes ineffective for the duration of the noise impulses.

4. A demodulator for frequency modulated carrier wave energy which comprises an electron discharge tube having an input electrode and an output electrode, a pair of resonant input circuits coupled to said input electrode, said resonant input circuits being oppositely mistuned by equal frequency amounts with respect to the center frequency of applied frequency modulation carrier wave energy, a resonant tank circuit providing a regenerative feedback coupling between said output electrode and said pair of resonant input circuits, said tank circuit being tuned to said center frequency, and a discriminator-rectifier having an input circuit coupled to said tank circuit.

5. A demodulator for frequency modulated carrier wave energy comprising an electron discharge tube having an input electrode and an output electrode, a pair of resonant input circuits coupled to said input electrode, said resonant input circuits being oppositely mistuned by equal frequency amounts with respect to the center frequency of applied frequency modulation carrier wave energy, a resonant tank circuit providing a regenerative feedback coupling between said output electrode and said pair of resonant input circuits, said tank circuit being tuned to said center frequency, means for converting modulated carrier voltage across the tank circuit into modulation signal voltage, and additional means, responsive to input energy above a predetermined amplitude, for automatically rendering said tube ineffective.

6. In a combination with a source of angular velocity-modulated carrier waves, a demodulator therefor which comprises a pair of resonant circuits, one of said resonant circuits being tuned to a frequency located a predetermined frequency amount on one side of the mean frequency of said waves, the second circuit being tuned to a fre-

quency located on the opposite side of said mean frequency at an equal frequency spacing value, means for applying said wave energy to both of said resonant circuits, an electron discharge tube system having an output circuit across which is developed modulation voltage, means connected to said applying means, responsive to a sudden noise impulse, having a control connection to said tube system for prevention operation of the latter for the duration of the impulse, and means for feeding back to said two resonant circuits oscillatory energy of said mean frequency.

7. In a frequency modulated carrier wave receiver, a demodulator comprising a pair of electron discharge tubes, each tube having at least an input electrode and an output electrode, a pair of resonant circuits oppositely mistuned by equal frequency amounts relative to the center frequency of the frequency modulated wave energy, a separate resonant tank circuit reactively coupling each of the aforesaid resonant circuits and a respective output electrode of each tube, said resonant tank circuits each being tuned to the aforesaid center frequency, and a common push-pull output circuit connecting said output electrodes.

8. In a frequency modulated carrier wave receiver, a network providing frequency modulated carrier wave energy, a demodulator comprising a pair of electron discharge tubes, each tube having an input electrode and an output electrode, separate resonant networks coupling said source to respective input electrodes of said tubes, said resonant circuits being oppositely mistuned by equal frequency amounts relative to the center frequency of the frequency modulated wave energy, a separate resonant tank circuit reactively coupling each of the aforesaid resonant circuits and a respective output electrode of each tube, said resonant tank circuits each being tuned to the aforesaid center frequency, a common push-pull audio output circuit connecting said output electrodes, and additional means, responsive to undesired noise impulses having an amplitude level above a predetermined value, for rendering said tubes ineffective for the duration of the noise impulses.

9. A demodulator for frequency modulated car-

rier wave energy which comprises an electron discharge tube having an input electrode and an output electrode, a pair of resonant input circuits coupled to said input electrode, said resonant input circuits being oppositely mistuned by equal frequency amounts with respect to the center frequency of applied frequency modulation carrier wave energy, a resonant tank circuit providing an oscillation-producing feedback coupling between said output electrode and said pair of resonant input circuits, said tank circuit being tuned to said center frequency, and means for deriving modulation signals from the tank circuit.

10. A demodulator for frequency modulated carrier wave energy which comprises an electron discharge tube having an input electrode and an output electrode, a pair of resonant input circuits coupled to said input electrode, said resonant input circuits being oppositely mistuned by equal frequency amounts with respect to the center frequency of applied frequency modulation carrier wave energy, a resonant tank circuit providing a regenerative feedback coupling between said output electrode and said pair of resonant input circuits, said tank circuit being tuned to said center frequency, means to derive modulation signal voltage from the energy developed across the tank circuit, and additional means, responsive to input energy above a predetermined amplitude, for automatically rendering said tube ineffective.

11. In combination with a source of frequency modulated waves, a detector provided with a frequency discriminatory network input, said network having an input circuit tuned to a predetermined frequency, said waves having a mean frequency substantially equal to said predetermined frequency, an oscillator tube provided with input and output electrodes and including said input circuit between its input and output electrodes as a regenerative coupling thereby normally to provide oscillations of said predetermined frequency, said oscillator tube being auxiliary to said detector, means coupling said source to said tuned input circuit thereby to cause said oscillations to vary in frequency in synchronism with the frequency variation of said waves.

HARRY E. THOMAS.
